UNITED STATES PATENT OFFICE.

DAVID DAVIES, OF SALT LAKE CITY, UTAH, ASSIGNOR, BY DIRECT AND MESNE ASSIGNMENTS, OF TWENTY-FOUR AND ONE-HALF ONE-HUNDREDTHS TO GEORGE F. SCHULTZ AND FIFTY-ONE ONE-HUNDREDTHS TO JOSEPH DECKER AND FINLY G. BROOKS, ALL OF SALT LAKE CITY, UTAH.

ATTACHMENT FOR HYDROCARBON-ENGINES.

1,278,116.

Specification of Letters Patent. Patented Sept. 10, 1918.

Application filed January 12, 1918. Serial No. 211,616.

To all whom it may concern:

Be it known that I, DAVID DAVIES, a citizen of the United States, residing at Salt Lake City, in the county of Salt Lake and State of Utah, have invented a new and useful Attachment for Hydrocarbon-Engines, of which the following is a specification.

This invention relates to an attachment for hydrocarbon engines whereby a mixture of air and water can be supplied in desired quantities to the gaseous fuel being supplied to an engine to increase the efficiency of the fuel and effect a considerable saving in the amount of fuel necessary.

Another object is to provide an attachment which can be applied readily to an engine, which is cheap to manufacture, can be cleaned readily, and is constantly under the control of the operator.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:

Figure 1 is a plan view of the attachment.

Fig. 2 is a section on line 2—2 of Fig. 1.

Fig. 3 is a plan view of the revoluble body of the attachment, the cap being removed.

Fig. 4 is an inverted plan view of the cap.

Referring to the figures by characters of reference 1 designates a stationary cap in the form of a disk having a central screw threaded stem 2 for engaging a supporting structure. A radial arm 3 is formed on the disk or cap and is provided with a laterally extending inlet port 4 opening into the passage 5 which extends through the arm 3 and has an outlet port 6 opening through the bottom of the cap. A needle valve 7 is mounted in the arm 3 so as to control the flow of water from the port 5 to the passage in the arm 3.

An aperture 8 is formed in the cap 1 and

extends entirely through it from top to bottom.

Extending from the center of the cap 1 is a tubular stem 9 on which a hollow cylindrical body 10 is mounted for rotation, this body being provided in its ends with openings 11 through which the stem 9 projects. That portion of the stem housed within the body 10 is provided with small apertures 12 communicating with the interior of the body. The free end portion of the stem 9 is screw threaded as at 13 for engagement with the manifold of an engine at a point between the carburetor and the inlet valve. A spring 14 is mounted on the stem and bears at one end against the body 10 and at its other end against a washer 15 which is detachably mounted on the stem, being held in place by a pin 16. This spring serves to hold the body pressed tightly against the cap 1. Formed in the body are spaced openings 17 and 18. When the opening 17 is in register with the port 6 the opening 18 is in register with the aperture 8. When the body 10 is turned upon the stem 9 communication between the openings in the body and the ports 6 and 8 will be simultaneously reduced or cut off as desired.

For limiting the relative movement of the body 10 and cap 1, spaced ears 19 are extended from the periphery of the body as shown particularly in Figs. 1 and 3. The cap 1 has a single ear 20 provided with a depending pin 21. This pin projects between the ears 19, and, by engagement thereby, limits the movement of the body.

An arm 22 is extended radially from the body 10 and may be connected to an actuating rod or the like, not shown, whereby the body 10 can be rotated readily.

As before pointed out the threaded end 13 of the stem 9 is to be attached to the manifold between the carburetor and the inlet valve. The port 4 is adapted to be placed in communication with the radiator or some other source of water supply. By means of the valve 7, the amount of water to be admitted to the attachment can be controlled. It will be obvious that by rotating the body 10 so as to bring ports 17 and 18 into communication with the ports 6 and 8, water will flow into the body 10 while air will also flow into said body. The suction created by the en-

gine will cause the water and air to pass through the apertures in the stem 9 so as to be mixed and the mixture will be drawn into the manifold and commingle with the fuel. 5 This will result in increasing the efficiency of the fuel. By shifting the arm 22 the amount of air and water admitted to the fuel can be controlled.

It will be seen that the device can be applied readily to a hydrocarbon engine and can be readily removed and cleaned, it merely being necessary to remove the pin 16 in order to permit separation of the parts.

What is claimed is:—

- 15 1. An air moistening attachment for hydrocarbon engines including a stationary member having air and water ports therein, valved means for controlling the flow of water to the water port, a tubular stem extending from said stationary member and open at one end, a hollow member mounted for rotation on the stem and having ports movable into and out of register with the respective ports in the stationary member, 20 there being outlet openings within the stem and communication with the interior of the movable member, and coöoperating means upon the members for limiting their relative movement.
- 25 2. An air moistening attachment for hydrocarbon engines including a tubular stem for attachment to the manifold of an engine, a cap carried by this stem and having air

and water ports therein, a valve for controlling the supply of water to the water ports, said stem having an apertured portion, a hollow body mounted for rotation upon the apertured portion of the stem and spaced ports, means for shifting said body to shift the ports simultaneously into or out of register with the respective ports in the stationary member, and resilient means for holding the two members pressed together. 35 40

3. An air moistening attachment for hydrocarbon engines including a tubular stem for attachment to the manifold of an engine, a cap carried by this stem and having air and water ports therein, a valve for controlling the supply of water to the water ports, said stem having an apertured portion, a hollow body mounted for rotation upon the apertured portion of the stem and spaced ports, means for shifting said body to shift the ports simultaneously into or out of register with the respective ports in the stationary member, and resilient means for holding the two members pressed together, 45 50 55

and coöoperating means upon the two members for limiting their relative movement. 60

In testimony that I claim the foregoing as my own, I have hereto affixed my signature in the presence of two witnesses.

DAVID DAVIES.
